UNITED STATES PATENT OFFICE.

GARRY J. DORMANDY, OF TROY, NEW YORK, ASSIGNOR OF ONE-HALF TO UNITED SHIRT AND COLLAR COMPANY, OF TROY, NEW YORK, A CORPORATION OF NEW YORK.

ELECTRIC-LAMP FIXTURE.

1,126,672.

Specification of Letters Patent. Patented Jan. 26, 1915.

Application filed June 25, 1914. Serial No. 847,343.

To all whom it may concern:

Be it known that I, GARRY J. DORMANDY, a citizen of the United States, residing at Troy, Rensselaer county, New York, have 5 invented certain new and useful Improvements in Electric-Lamp Fixtures, of which the following is a specification.

My invention relates to fixtures adapted to stand upon and be secured to a table or the 10 like and to carry one or more, usually two, incandescent lamps, adjustable to a great variety of different positions with respect to the table or machines thereon. A series of such fixtures connected by conduits beneath 15 the table and providing means for protecting the conducting wires or cables from being cut or injured in any way, while permitting the freest movement of each lamp, is provided by my invention, further objects 20 of which will appear in this specification and be pointed out in the claims.

In the drawings, which represent a preferred form of my device, Figure 1 is a front elevation, partly broken away, of a 25 single standard and all connecting parts embodying my invention; Fig. 2 is a like view showing a swivel and adjacent parts detached; Fig. 3 is a vertical section through the plane 3—3, Fig. 2.

30 Premising that the fixtures are largely used in factories and mills on long tables carrying double rows of machines, as sewing machines, 11 designates a part of such table, shown in section, on which is secured, 35 as by screws 12, a standard 13 comprising a flanged column 14, a rectangular box-holding portion 15, two oppositely extending arms 16, each terminating in a vertical split socket 17 having a set screw 18. In each 40 socket 17 is the vertical rotary member 19 of a double swivel 20, the upper member 21 of which is a split socket, provided with set screw 22, for the pin 23 of a horizontally 45 swinging part 24, shown as provided with two longitudinally disposed apertures 25, which may have set screws 26, for supporting a tube 27, at the outer end of which is secured an incandescent lamp 28. A double 50 insulating plug socket 29 is secured within part 15 of standard 13, the plug members 30 of which are connected by conducting cables 31, passing through tubes 27, to the sockets of lamps 28. A cable 32 passes through conduit 33 and is looped or branched upward 55 through box 34, downward extension 35,

which is screwed into an insulating block in the foot of column 13, through the column, and to each side of the stationary portion of socket 29.

The operation of the device will be readily 60 understood from an inspection of the drawings.

Any desired number of standards 13 may be placed along the central longitudinal line of table 11, all connected by conduit 33. The 65 wiring is clearly shown in Fig. 1. By the rotation of part 19 in socket 17, the lamp carrying tube 27 may be extended longitudinally of the table, as shown, transversely thereof, or at any intermediate angle. In 70 like manner the rotation of part 24 permits the elevation or depression of the lamp, while tube 27 is capable of both rotary and longitudinal movement in apertures 25. Screws 18, 22 and 26 may be adjusted either 75 to provide desired frictional resistance to the movement of parts 20, 24 and 27, or to lock them in set position.

It is obvious that certain mechanical changes may be made in my device without 80 departing from my invention, e. g., it is evident that the double-swiveling connection between the standard and the arms 27 is non-essential to my device in its broadest view.

An important advantage of the invention lies in the fact that all the conducting cables, as 32, are not only fully inclosed in conduit tubes, but also that they are positioned below the table or work-bench, where they cannot 90 under any circumstances come into contact with the work. These devices are largely used on long tables crowded with sewing machines, which are used for stitching very light and inflammable materials, as cotton 95 or silk. In many cases, where the wires were carried above the table, serious fires, with loss of life, have been caused by a short circuit or other accident.

What I claim is:

1. An electric lamp fixture including a standard constructed and fitted to be secured to a table; tubular means extending downward from said standard and supported thereby and adapted to pass through such table; a box at the lower end of said tubular means fitted to receive the ends of horizontal conduit tubes; oppositely extending arms at the top of said standard; lamp carrying tubes having swiveled connection 105 110

with said arms; and an insulating box at the top of said standard, substantially for the purposes set forth.

2. An electric lamp fixture including a standard constructed and fitted to be secured to a table; a pipe nipple extending downward from said standard and supported thereby and adapted to pass through such table; a box at the lower end of said nipple adapted to receive the ends of horizontal conduit tubes; oppositely extending arms at the top of said standard; a swivel member carried by each of said arms; a lamp carrying tube fitted for longitudinal and rotary movement with respect to said swivel member; and an insulating box at the top of said standard between said arms, substantially for the purposes set forth.
3. An electric lamp fixture including a standard constructed and fitted to be secured to a table; a block of insulating material secured at the foot of said standard; a nipple secured in said block so as to be supported by said standard and to pass downward through such table; a box at the lower end of said nipple adapted to receive the ends of horizontal conduit tubes so as to support said tubes; and a lamp carrying tube having swiveled connection at the top of said arm.
4. An electric lamp fixture including a standard constructed and fitted to be secured

to a table; a block of insulating material secured within the foot of said standard; a nipple secured in said block so as to be supported by said standard and to pass downward through such table; a box at the lower end of said nipple adapted to receive the ends of horizontal conduit tubes so as to support said tubes; oppositely extending arms at the top of said standard; lamp carrying tubes each having a swiveled connection with one of said arms; and an insulating box at the top of said standard, substantially for the purposes set forth.

5. An electric lamp fixture including a standard constructed and fitted to be secured to a table; tubular means extending downward from said standard and adapted to pass through such table; a box at the lower end of said tubular means fitted to receive the ends of horizontal conduit tubes; oppositely extending arms at the top of said standard; lamp carrying tubes having swiveled connection with said arms; and an insulating box at the top of said standard providing separate plug connections for a cable passing through each of said tubes, substantially for the purposes set forth.
